UNITED STATES PATENT OFFICE.

JESSE D. TUCKER, OF SACRAMENTO, CALIFORNIA, ASSIGNOR TO TUCKER BROTHERS MANUFACTURING COMPANY, OF SACRAMENTO, CALIFORNIA.

SPRING-AXLE CONSTRUCTION.

Application filed October 29, 1923. Serial No. 671,402.

To all whom it may concern:

Be it known that I, JESSE D. TUCKER, a citizen of the United States, residing at Sacramento, county of Sacramento, and State of California, have invented certain new and useful Improvements in Spring-Axle Construction; and I do declare the following to be a full, clear, and exact description of the same, reference being had to the accompanying drawings, and to the characters of reference marked thereon, which form a part of this application.

This invention relates to improvements in vehicle-axle construction, in which leaf springs are used not only to function as springs, but are arranged to take the place of the usual rigid axles as well, thus combining in a single unit the properties of both springs and axles.

20 The present invention particularly represents an improvement over that type of spring-axle shown in my copending application for patent filed February 6th, 1923, Serial No. 617,262, my main object now being to arrange the springs which form the axle in such a manner that breakage of any one spring—a not uncommon occurrence—will not allow the wheel-spindles supported by said springs to become misaligned or to sag—something which if permitted to happen, would be fraught with great danger to the occupants of the vehicle.

Another object is to provide means for preventing any steerable or front wheels which may be mounted with my spring axle, from toeing in or out with the unavoidable deflection of the springs when the vehicle is travelling over a more or less rough road.

Such a movement on the part of the wheels, if allowed to take place, would not only make steering a harder job than usual or necessary, but would cause undue wear on the tires.

These undesirable features I have eliminated with my improved arrangement.

I have also provided a simple means for preventing longitudinal slippage of the vertically spaced springs relative to each other, such as would cause misalignment of the

wheel spindles and possible accidents resulting therefrom.

These objects I accomplish by means of such structure and relative arrangement of parts as will fully appear by a perusal of the following specification and claims.

In the drawings similar characters of reference indicate corresponding parts in the several views:

Fig. 1 is a perspective outline of the front end of an automobile of well known make, showing the preferred type of multiple-spring axle installed thereon.

Fig. 2 is a top plan view of the spring axle.

Fig. 3 is an end view of a spindle-supporting yoke, with the springs and radius-rods as connected thereto.

Fig. 4 is a front view of the multiple-spring axle construction as applied to a trailer.

Figs. 5 and 6 are front and top plan views respectively of a modified form of multiple-spring axle.

Fig. 7 is a fragmentary perspective view of a number of spring-leaves, showing the means employed to prevent longitudinal slippage of the same relative to each other.

Referring now more particularly to the characters of reference on the drawings, and particularly at present to Figs. 1 to 3, the numeral 1 denotes the usual wheel-supporting spindles mounted in bodies 2, which in turn are turnably mounted in specially formed yokes 3.

The bodies 2, as is customary, have rearwardly extending arms 4 which are connected as usual at their rear ends by the cross-tie rod 5. The yokes are formed on their adjacent faces with a plurality of evenly spaced and vertically aligned ears 6, at least three in number, to receive the bolts or pins 7 which form supports for the usual eyes on the ends of vertically spaced leaf-springs 8, preferably quite flat when supporting a normal load. These springs are parallel to each other and of equal lengths, and extend between and connect the yokes. Spacer-blocks 9 are placed between the springs at their centers of length, and said

blocks and springs are clamped to the cross-frame member 10 of the car by suitable U-bolts 11 or other clamping means.

To brace the yokes, and prevent twisting thereof, and of the springs in a plane longitudinally of the vehicle, I preferably connect radius rods 3^a thereto, which rods extend rearwardly to a suitable connection with the chassis of the car, as is customary.

10 To render this bracing as effective and yet as simple as possible, each yoke has two of such rods, connected thereto at top and bottom by means of the same bolts 7 which connect the springs to the yoke.

15 It will be evident that with this construction, as the springs are deflected or depressed at the center, the wheels 12 of the car will of course be moved somewhat apart from each other, but this movement I have reduced to a minimum by designing the springs so as to be very nearly flat when under normal load, as specified.

20 There will naturally however be some slight lateral deflection of the spindles and wheels as the springs flex. If the rod 5 extending between the arms 4 was a straight rigid nonflexing member this would hold the ends of said arms fixed irrespective of any lateral deflection of the spindle supports and wheels. This condition would therefore tend to move the spindle supports on their pivotal points and toe the wheels in or out as the springs flexed up and down which would be an objectionable feature.

35 To overcome this objection I form the rod 5 of flexible material and give it substantially the same curvature as the spring elements. (See Fig. 5.) I then connect a rigid bracket 14 with one of the spacing blocks 9 and provide a yoke 13 on its outer end to slidably engage the rod 5. Then as the springs flex up and down this bracket will likewise flex the rod 5 and keep the ends of the arms 4 spaced the same at all times with respect to the spacing between the spindle supports and wheels. This will prevent any toeing action of the latter.

40 In Fig. 4, the same arrangement of springs 8^a is shown as in the type just described, but said springs are attached to members 15 which directly support the non-steerable wheel-spindles 16.

45 This type of arrangement is for trailers, or the rear wheels of automobiles, and to enable the height of the trailer frame or body from the ground to be easily altered if desired, the spindles 16 are disposed on the members 15 in a plane intermediate two of the springs and said members being reversible, the spindles will either be above or below the center of height of the members, as will be evident.

50 In Figs. 5 and 6, a modified form of multiple spring arrangement is provided. In this form of spring-axle, two sets of verti-

55 cally spaced springs 17, connected to the yokes 18, are used; each set comprising at least a pair of springs horizontally aligned and spaced sufficient to permit of lugs 19 from the yokes projecting therebetween at 70 the ends.

60 The arrangement of the three spring elements spaced in parallel relation as shown prevents a tipping over of the spindle supports in the event that one spring element 75 breaks, since the other two still function to hold the spindle supports in proper vertical position. A car therefore equipped with this latest type may therefore be operated with 80 safety, if due caution is used, even though any one of the springs should be broken by some unfortunate occurrence.

65 In all types, the adjacent faces of the leaves and the spacer blocks are knurled or otherwise indented as shown at 20, so that when the springs and blocks are clamped to the car, they will be firmly locked together 85 without throwing all the strain on the holding bolts or clamps, and without the possibility of the springs slipping sideways of the 90 car and relative to each other, such as would cause the yokes and spindles to be moved to set at an angle out of their proper plane.

70 From the foregoing description it will be 95 readily seen that I have produced such a device as substantially fulfills the objects of the invention as set forth herein.

75 While this specification sets forth in detail the present and preferred construction of the device, still in practice such deviations from such detail may be resorted to as do not form a departure from the spirit of the invention, as defined by the appended 100 claims.

80 Having thus described my invention what 105 I claim as new and useful and desire to secure by Letters Patent is:

85 1. A spring axle structure comprising vertically spaced spring elements, pivoted spindle supports connected with the free ends of the spring elements, steering connections between the supports, and means whereby, when the flexing of the spring elements move the spindle supports apart, the steering connections will not move such spindle supports on their pivotal points.

90 2. A spring axle structure comprising vertically spaced spring elements, pivoted spindle supports connected with the free ends of the spring elements, steering connections between the supports, and means whereby, when the flexing of the spring elements move the spindle supports apart, the steering connections will not move such spindle supports on their pivotal points, such means including instrumentalities co-operating between the spring elements and steering connections to cause the latter to conform to the flexing action of such spring elements.

95 3. A spring axle structure comprising ver-

tically spaced spring elements, pivoted spindle supports connected with the free ends of the spring elements, steering connections between the supports, and including arms on the spindle support and a flexible rod connecting the arms, a bracket rigid with the spring elements, and a yoke on the bracket engaging the flexible rod in sliding relation

whereby when the springs flex and move the spindle supports apart, the yoke will flex ¹⁰ the rod a like amount and thus prevent the rod from pulling on the arms and moving the spindle supports on their pivotal points.

In testimony whereof I affix my signature.

JESSE D. TUCKER.
